CLAIM

The ornamental design for block body of wire connection terminal, as shown and described.

DESCRIPTION

FIG. 1 is a front side perspective view showing our new design for block body of wire connection terminal;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top view thereof;

FIG. 7 is a bottom view thereof; and,

FIG. 8 is a bottom side perspective view thereof.

The broken lines in the drawings illustrate portions of the block body of wire connection terminal that form no part of the claimed design.
